UNITED STATES PATENT OFFICE.

WILLIAM H. STEWART, OF KANSAS CITY, KANSAS, ASSIGNOR OF ONE-HALF
TO HORATIO N. STRAIT, OF SAME PLACE.

CAR-COUPING.

SPECIFICATION forming part of Letters Patent No. 421,361, dated February 11, 1890.

Application filed September 23, 1889. Serial No. 324,799. (No model.)

To all whom it may concern:

Be it known that I, WILLIAM H. STEWART, of Kansas City, Wyandotte county, Kansas, have invented certain new and useful Improvements in Car-Coupling Devices, of which the following is a full, clear, and exact description, reference being had to the accompanying drawings, forming a part thereof.

My invention relates to improvements in car-coupling devices; and it consists in the novel construction and arrangement herein-after set forth and described.

In the drawings which illustrate the manner of carrying out my invention, Figure 1 is a central vertical section of two draw-heads, one showing the link held in position by my improved coupling-pin, the other with the pin in position for the drop when said couplings shall come together. Fig. 2 is a perspective view of my invention, showing the link and coupling-pin in position. Fig. 3 is a detail in perspective of the pin with my improved abutment rigidly attached thereto.

Referring to the drawings by letter, A represents my invention; B, the coupling-pin, having rigidly secured to its rear surface a square shoulder or abutment B', for the purpose herein described.

C and C' are bearings on which the coupling-link b rests when in position to be coupled to an adjoining car, where the draw-heads are at an equal elevation.

D is a square slot in the draw-head immediately behind and connected with the hole c. Said slot D is made in such a manner as to form a proper receptacle and guide for abutment B'.

E is the draw-head, the shape of which is the same as those now in common use, but embodying my improvements herein described.

a is the lower terminus of the abutment B', this point bearing on the end of coupling-link b, and serves to hold said coupling-link b in an almost horizontal position.

d are the rounded shoulders of draw-head E and serve to guide the coupling-link b to the proper point.

e is a notch made in the lower end of the

coupling-pin and serves to hold the same in position (illustrated in Fig. 1) before the link is inserted in the draw-head. This, however, I do not claim as being a part of my invention.

The draw-head E has upon its upper surface a casting E', which forms an additional support for the coupling-pin when not in use, as illustrated in Fig. 1.

To use my coupling device where the cars to be coupled are of different heights, I raise or lower the coupling-pin B, thereby bringing the coupling-link b in any desired position. (Illustrated by dotted lines in Fig. 1.)

Heretofore coupling-pins have been made with a head at their upper surface, which serve to hold it in position, but having no effect on the coupling-pin other than to keep it from dropping from the draw-head. In my improved method of making this pin I utilize the weight of said pin B and abutment B' to hold the coupling-link in a horizontal position. I do this by means of bearings C and C', heretofore referred to. When the cars to be coupled are of the same height, the bearings C and C' serve to form a rest for link b, which link is held steady by the weight of pin B and abutment B', as heretofore described. If the cars to be coupled are of different heights, the link is brought in position by raising or lowering the coupling-pin B, thus operating the link b, as shown by dotted lines, Fig. 1. This improved method of operating said link B will be found much easier and simpler than the old way and obviates the necessity of taking hold of the link with the hand and holding it in position, which in many cases has been the cause of serious accidents. The slot D is made only in the upper portion of the draw-head and of the desired shape and size to receive and hold the abutment B'.

Having thus fully described my invention, what I claim as new, and desire to secure by Letters Patent, is—

1. In a draw-head, a casting E', for supporting the pin when not in use, a circular aperture having in connection therewith a

slot for the reception of the coupling-pin, and lugs C C', on which the link is adapted to rest, substantially as described.

2. The combination, with a draw-head having a casting E', a circular aperture connected with a slot for the reception of the coupling-pin, and lugs C C', of a coupling-link held in position by a pin B, said pin being formed

with a longitudinal lug, substantially as described.

In testimony whereof I affix my signature in presence of two witnesses.

WILLIAM H. STEWART.
